[57] ABSTRACT

A cementation tab having a pressure sensitive adhesive surface serves as a carrying and manipulating tool for dental bands, crowns and inlays. When used to carry a band it, with the band, forms a containing cup for cement, and also may be used to wipe away excess cement.

CEMENTATION TAB

DESCRIPTION

This invention relates to an improved dental tool, and more particularly to a cementation tab.

An object of the invention is to provide an improved dental tool.

Another object is to provide a cementation tab.

A further object of the invention is to provide a tab for holding and carrying elements to be placed on teeth.

Another object of the invention is to provide a cementation tab having a pressure sensitive adhesive surface on which an end of a band is placed to form a cup or container to confine cement placed in the band and for carrying the band and placing it over a tooth.

Another object of the invention is to provide a cementation tab having a body sheet, a pressure sensitive adhesive surface, a handle strip covering one end portion of the adhesive surface and a removable cover sheet covering and adhered to the adhesive surface.

IN THE DRAWINGS

FIG. 1 is a perspective view of a cementation tab forming one embodiment of the invention; and,

FIG. 2 is a perspective view of the tab of FIG. 1 with a removable cover sheet removed and a dental band adhered to the tab and forming a handled cup therewith.

Referring now in detail to the drawings, there is shown therein cementation tabs 10 forming one embodiment of the invention and secured together in an elongated strip 9 of pressure sensitive tape having weakened perforated tear lines 13 separating the tabs, the tabs 10 forming remainder 11 of the strip being shown in broken lines. Each tab includes a short section of the tape defining a body sheet 12 of paper and a thin surface layer 14 of the pressure sensitive adhesive. The tape may be a commercially available pressure sensitive adhesive tape with the tear lines provided. Handles 16 of a strip of stiff paper are adhered to end portions of the adhesive surfaces 14 to form non-sticky handle portions, and each of peelable covers 18 comprises a thin sheet of foil, plastic, or waxy or hard surfaced paper to protect the surface 14 during storage and handling of the tab prior to its use. If desired, the tabs may be separated from each other for storage in piles. An end portion 20 of the cover overlaps the handle 16 and may be grasped easily to peel the cover off the tab.

For placement of a dental band 22 (FIG. 2) having a bracket, tube or other attachment 15 over a tooth and cementing it to the tooth, a planar outer end 24 is pressed against the adhesive surface 14 to form a cup-like container with the tab, a shaped non-planar inner or gum end 26 of the band forming the top end of the container. Cement may be applied to the interior of the band after this formation of the container by a simple wiping operation, and the tab retains the cement in the band. Then, when the band is to be placed over the tooth, the handle is grasped and the tab is moved with the band and is manipulated to place the band over the tooth, inverting being effected at the last moment for placement on a lower tooth. The tab then is peeled off the band, and may be used to position the band, wipe away excess cement and smooth exposed portions of the cement. The tab then is discarded.

The tab 10 may also be used to carry and place crowns and inlays with cement thereon, and is a very useful carrying tool. The tab eliminates messiness in handling dental inserts, and is a very convenient tool. In an alternate form of the invention, a roll of pressure sensitive tape having one edge portion free of adhesive, is dispensed by a conventional tape dispenser, short lengths being torn off by a serrated knife of the dispenser to form tabs with said edge portion forming non-adhesive handle portions on the tabs.

What is claimed is:

1. A dental cementation tab comprising a flexible sheet having a non-adhesive handle portion at one edge thereof and a carrying portion having an adhesive on one face thereof at the central portion thereof of a size sufficient to hold a dental member such as a band, crown, inlay or the like to be attached to a tooth,

the tab when in a position with the adhesive uppermost serving to receive a band and form a cup with the band to hold cement and being of a small size so as to be easily movable into the mouth of a patient and be easily manipulated therein for placing the band on a tooth in the mouth.

2. The dental cementation tab of claim 1 wherein the handle portion includes a non-adhesive strip secured to one end portion of the sheet.

3. The dental cementation tab of claim 1 wherein the sheet comprises a short section of pressure sensitive adhesive tape.

4. The dental cementation tab of claim 1 wherein said one face except for the handle portion is covered entirely with pressure sensitive adhesive and is adapted to adhere to an end of a band to form a cup therewith and also is adapted to adhere to a crown or an inlay.

5. The dental cementation tab of claim 4 wherein the handle portion includes a non-adhesive strip secured to one end portion of said face by the adhesive.

6. A dental cementation tab comprising:
a sheet of pressure sensitive tape,
a non-adhesive handle secured to one edge portion of the adhesive face of the sheet,
and a removable cover of non-adhesive material covering the remainder of the sheet,
the remainder of the sheet when said cover is removed being sufficiently wide to receive and adhere to a dental member such as a band, crown, inlay or tube to be cemented to a tooth in the mouth of a patient,

the tab being sufficiently small to be grasped and manipulated by a thumb and forefinger and to be moved into the patient's mouth and manipulated to position the dental member where desired on the tooth and then stripped from the dental member.

7. A dental cementation structure comprising an elongated strip having a face covered except for one edge portion with a pressure sensitive adhesive and said edge being free of adhesive, the strip being separable into short lengths to define tabs having non-adhesive handle portions, the covered portion of each tab being sufficiently large in area to receive a dental member such as a band, inlay or the like to be cemented to a tooth in a patient's mouth,

each tab being not substantially larger than the dental member so that the tab may be manually inserted into the patient's mouth and manipulated in the mouth to position the dental member where desired on the tooth.

8. The dental cementation structure of claim 7 wherein the strip has serrated tear portions to facilitate forming the tabs.

9. The dental cementation structure of claim 7 including a strip of stiff paper adhered to the adhesive to define said edge portion.
